DESIGN FOR A CRIB

Earle E. Merrett, Manitowoc, Wis., assignor to
Hamilton Manufacturing Company, Two
Rivers, Wis., a corporation of Wisconsin

Application October 3, 1941, Serial No. 103,623

Term of patent 7 years

To all whom it may concern:

Be it known that I, Earle E. Merrett, a citizen
of the United States, residing in Manitowoc, in
the county of Manitowoc, State of Wisconsin,
have invented a new, original, and ornamental
Design for Cribs, of which the following is a
specification, reference being had to the accom-
panying drawing, forming a part thereof, where-
in:

Figure 1 is a perspective view of a crib, showing
my new design; and

Fig. 2 is a front elevational view thereof.

The dominant features of the design reside in
the portions shown in full lines in Figures 1 and 2.

I claim:

The ornamental design for a crib, substantially
as shown and described.

EARLE E. MERRETT.
